UNITED STATES PATENT OFFICE

122,805

DESIGN FOR A WINDOW SEAT

Jennie Sweetwine, Detroit, Mich.

Application July 24, 1940, Serial No. 93,882

Term of patent 7 years

To all whom it may concern:

Be it known that I, Jennie Sweetwine, a citizen of the United States, residing at Detroit, county of Wayne, in the State of Michigan, have invented a new, original, and ornamental Design for a Window Seat, of which the following is a specification, reference being made to the accompanying drawing, forming part thereof.

Fig. 1 is a front view, in perspective, of a window seat showing my new design.

Fig. 2 is a side elevational view thereof.

Fig. 3 is a front elevational view thereof.

I claim:

The ornamental design for a window seat, as shown.

JENNIE SWEETWINE.
